UNITED STATES PATENT OFFICE.

EDWARD S. DAVIS, OF JERSEY CITY, NEW JERSEY, ASSIGNOR TO ROCKWELL FURNACE COMPANY, A CORPORATION OF NEW YORK.

ROTARY FURNACE.

1,010,728.

Specification of Letters Patent.

Patented Dec. 5, 1911.

Application filed September 29, 1909. Serial No. 520,106.

To all whom it may concern:

Be it known that I, EDWARD S. DAVIS, a citizen of the United States, and a resident of Jersey City, in the county of Hudson and State of New Jersey, have invented certain new and useful Improvements in Rotary Furnaces, of which the following is a specification.

My invention relates to improvements in rotary furnaces, and particularly to furnaces of this type which are fired by liquid or gaseous fuel. It is essential to the successful operation of a furnace of this sort that the blanks or articles which are being annealed, tempered or heat treated, all be heated to the same uniform degree, and for this reason all the blanks should be fed through the furnace at the same even rate of travel. Heretofore it has been customary to provide furnaces of this character with a helical lining which acted, as the furnace revolved, in the capacity of a screw-thread to advance the articles under treatment from the inlet to the discharge end of the furnace. This helical lining serves its purpose so long as the articles or blanks are smooth and regular in shape. But this sort of lining is not adapted for handling rough or irregular blanks, for when the blanks are rough or irregular in shape, there is a tendency for them to become caught and stick in the screw-thread grooves of the lining, and this results in an uneven heating of the blanks.

It is one of the objects of my invention to handle these irregular shaped articles and to provide for their even passage through the furnace, thereby assuring a uniform heating of all the articles.

Another object of my invention is to regulate the heating of the articles to any desired degree.

Heretofore it has been the practice to discharge the articles from the furnace intermittently, as by way of a trap door in the wall of the furnace which was opened at regular intervals as the furnace rotated. This intermittent discharge is objectionable, in that, some of the articles are heated more than others because in each discharge the first articles to arrive at the discharge point receive more heat than the later ones to arrive, and also, in that, the operation of the furnace is discontinuous.

A further object of my invention is to overcome these objections by insuring a continuous operation of the furnace and a uniform heating of the articles or material.

In its preferred form the invention consists of a cylindrical furnace body which is mounted to rotate and which is provided with a plain unobstructed lining. This plain lining permits articles of any irregular shape, such as bolts and the like, to be handled, and the feeding of the blanks is accomplished by tilting or inclining the furnace body. The inclined position of the furnace, together with the revoluble movement, causes the blanks to be fed forward in a spiral sort of movement. The speed of travel through the furnace, and hence the degree of heat, may be regulated by adjusting the inclination of the furnace body.

Another feature of the invention resides in the provision of a relatively stationary head which is located at one end of the furnace and has a bore or opening corresponding to the opening in the furnace body. This stationary head carries the outlet from the furnace, preferably in the form of a discharge chute, so that the articles may pursue an unobstructed path from the revolving furnace body into the stationary head and out through the discharge outlet therein.

Various other minor features of the invention will appear as the specification proceeds.

A preferred embodiment of the invention is illustrated in the accompanying drawings, but it will be understood that various modifications and changes may be made without departing from the spirit and scope of the invention.

In the drawings: Figure 1 is a side elevation, with parts broken away, of the furnace in its normal tilted position. Fig. 2 is an end view of the furnace, in the horizontal non-tilted position.

Like reference characters denote like parts throughout the several views.

The furnace body consists preferably of a cylindrical casing or shell 1, having a plain unobstructed lining 2. This lining is preferably of cylindrical shape to provide a continuous passage or opening from end to end of the furnace. This opening of furnace chamber need not, for all purposes, however,

be made cylindrical, as it could be made to taper in diameter from end to end. The furnace is rotated preferably by means of the rollers 3, upon which it is supported and these supporting rollers may be driven by suitable gearing, such as the bevel gear 4, pinion 5, sprocket 6, chain 7, and sprocket-pinion 8.

The furnace as a whole is carried by a support, preferably such as the frame 9, which is pivoted at the point 10, upon a foundation or support 11, so as to be capable of a tilting movement. The means for tilting or inclining the furnace may consist of any suitable mechanism but it preferably consists of a handwheel 12, which, by means of bevel gears 13-14, imparts a rotary movement to a worm (not shown) in line with gear 14, which worm in turn imparts movement to a wormwheel 16 on the shaft 17, and also on said shaft is a spur pinion 18, meshing with a dependent rack 19, on the supporting frame. It will be obvious that by turning the handwheel, the inclination of the furnace may be adjusted at will. In order that the furnace may be rotated regardless of its tilted position, the driving connections for rotating the same preferably have a center of movement corresponding to the pivotal connection between the foundation and supporting frame. For this reason the sprocket-pinion 8, or other driving connection, as the case may be, preferably moves on a center corresponding to the pivot 10, as shown, or as a matter of fact, this driving member may be journaled direct on the extended end of the pivot. Motion is imparted to the driving member by means of a belt on the pulley 21, or other such suitable devices.

A feed hopper 22 is located at one end (the upper end) of the furnace and this hopper may, if desired, be carried by and rotate with the furnace, but for handling irregular material I prefer to employ a stationary hopper, such as shown, which is supported on the end of the frame by means of a bracket 23. A flanged rim 24, is preferably provided to overlap the mouth of the hopper to prevent any loss of heat, and, if desired, the hopper may be provided with a charging door (not shown). Located at the opposite end of the furnace, (which is normally the lower end) there is provided a relatively stationary head 25, and the interior of this head has a compartment or opening 26, which forms a continuation of the furnace chamber. The burner 27, is carried by the head and discharges into the furnace chamber. The fuel feeding connections are preferably jointed at a point in line with the pivotal support of the furnace, so that the burner may operate irrespective of the tilted position of the furnace, but as this is a common feature, it has not been illustrated. The

outlet from the furnace is also preferably carried by the head and in the present instance this consists of a discharge chute 28. The mouth of the discharge chute is in direct communication with the chamber in the head, so that in this way a free unobstructed passage for the blanks is provided from the inlet hopper at one end of the furnace, out through the discharge chute at the opposite end of the furnace. This discharge chute may be secured to the frame and it will then serve conveniently as a means for supporting the head.

As the articles pass out of the discharge chute they are received in a suitable receptacle and this receptacle may provide a hardening or cooling bath for the articles. For this reason the receptacle would preferably be in the form of a tank 29, into which the lower end of the chute dips. This tank would be supplied with a cooling liquid by suitable pipe connections 30. Also the level of the liquid in the tank would be regulated to provide a seal for the lower end of the chute. There would also preferably be provided an inclined conveyer 31, for elevating and discharging the cooled articles from the tank. To prevent any of the blanks or articles from falling to the extreme bottom of the tank, and out of reach of the pockets in the conveyer, there would preferably be provided an inclined guide 32, supported from the wall of the tank at the point 33, and preferably hinged there so that its lower end will remain in contact with the wall of each succeeding pocket of the conveyer. I also provide means for taking up the thrust of the furnace body when the same occupies an inclined position. This means would preferably consist of one or more thrust rollers 34, journaled on brackets 35, and adapted to be engaged by an outstanding annular flange 36, on the furnace body.

What is claimed is:

A furnace comprising: a support, a tiltable frame mounted thereon, means for adjusting the inclination of said frame, an open-ended cylindrical furnace body journaled to rotate on the frame, said body having a cylindrical furnace lining, an inlet hopper carried by the upper end of the frame to cooperate with and form substantially a closure to the open upper end of the furnace body, a stationary head mounted on the lower end of the frame, said stationary head having an interior furnace lining to provide a stationary outlet chamber, which chamber conforms to and constitutes a stationary continuation of the rotary furnace chamber so as to receive the articles direct from the furnace chamber, a discharge chute leading downward from the outlet chamber, the stationary head having a burner opening in the end of the same, communicating with the outlet chamber therein, a burner support

ed by the stationary head and discharging through the burner opening therein into the outlet chamber, fuel feeding connections to the burner, and driving connections for rotating the furnace body, having a center of movement corresponding to the center of pivotal support of the tiltable frame.

Signed at New York in the county of New York and State of New York this 27th day of September A. D. 1909.

EDWARD S. DAVIS.
